HEAT TRANSFER MEDIUM

Herbert Wilkens Daudt and John Elton Cole,
Wilmington, Del., assignors to E. I. du Pont
de Nemours & Company, Wilmington, Del., a
corporation of Delaware

No Drawing. Application June 21, 1932
Serial No. 618,564

9 Claims. (Cl. 62—178)

This invention relates generally to the art of transferring heat from one point or body to another, and more particularly to refrigeration which is secured by vaporization of gaseous 5 compounds or mixtures which have been condensed to their liquid state.

Numerous gases have been used as refrigerants for producing moderately low temperatures, such as are required in the ordinary 10 household or small commercial refrigeration units. Most of these refrigerants are objectionable in that they present certain hazards owing to their toxicity, instability or inflammability.

When very low temperatures are desired certain 15 refrigerants present other difficulties, for instance, the solidification of the refrigerant at temperatures higher than desired. This results in the formation of solid masses at points in the refrigeration system which may interfere with 20 the operation thereof. Thus, under certain conditions carbon dioxide solidifies if allowed to cool to or below certain desirable temperatures.

This invention has as an object the provision 25 of a new and improved refrigerant and a process of refrigeration employing that refrigerant. Another object is to provide a refrigerant which is non-inflammable, practically non-toxic, and stable under operating and atmospheric conditions. A further object is to provide a refrigerant 30 of low boiling point, low affinity for water, and a solidification point low enough to prevent blockage of the refrigeration system by freezing of the refrigerant at any stage in the heat transfer cycle. Other objects will appear herein- 35 after.

These objects are accomplished by evaporating and condensing a compound of sulfur, oxygen, and fluorine such as sulphydryl fluoride (SO_2F_2) in a heat transfer system. This compound 40 is noninflammable and very stable, being practically inert under both operating and atmospheric conditions. Also, as far as it has been ascertained, its toxicity is very low. Sulphydryl fluoride boils at a temperature of 45 $-52^\circ C.$ at atmospheric pressure, and solidifies at the much lower temperature of $-120^\circ C.$ It further possesses the property of having practically no affinity for water under the usual operating temperature for any refrigerating or 50 heat transfer system in which it might be used.

Sulphydryl fluoride, may be advantageously used in well-known types of refrigeration systems such as, for example, the so-called flooded and dry systems. By a flooded system is meant 55 one in which a relatively larger amount of the

liquid refrigerant is retained in the evaporator and evaporation takes place from the surface of the liquid as a result of the reduction of surface tension of the liquid. The dry system is that type in which the evaporation of the liquid takes place during its release through an expansion or regulating valve into the cooling chamber or coils. The liberated gas may be condensed by compression and cooling or in any other suitable manner. If desired, the system may include a suitable absorbent for the gas liberated. Sulphydryl fluoride is also adapted for use as a cooling agent by spraying the liquid refrigerant over the article to be cooled and permitting evaporation therefrom, or by immersing the body to be cooled in the liquid refrigerant, and by similar processes.

Sulphydryl fluoride possesses the necessary physical characteristics of a good refrigerant since, as shown above, it boils at a low temperature and solidifies at a considerably lower temperature. A refrigerant of such a low freezing point and such a wide difference between freezing and boiling points would not solidify within a refrigeration system under any usual range of 80 operating temperatures, and thereby eliminates one of the objections to the more common refrigerants now employed. Since it has low affinity for water it is easily maintained in dry 85 form.

As an illustration of another compound falling within the broader aspects of the invention thionyl fluoride (SOF_2) may be mentioned. It has a somewhat higher boiling point ($-31^\circ C.$) than sulphydryl fluoride but is less desirable from 90 the standpoint of stability.

As many apparent and widely different embodiments of this invention may be made without departing from the spirit thereof, it is to be understood that we do not limit ourselves to 95 the foregoing description except as indicated in the following claims.

We claim:

1. The process of transferring heat, which 100 comprises condensing a gaseous substance containing a compound of sulphur, oxygen and fluorine, and evaporating the condensate.

2. The process of transferring heat, which 105 comprises condensing a gaseous substance containing a compound having the following general formula:

wherein x is an integer not greater than 2, and 110 evaporating the condensate.

3. The process of transferring heat, which comprises condensing a gas containing sulphuryl fluoride, and evaporating the condensate. 80
4. The process of transferring heat, which comprises condensing a gas containing sulphuryl fluoride, and evaporating the condensate or a portion thereof in the vicinity of a body to be cooled. 85
5. The method of refrigeration which comprises liberating, subject to control at a relatively low pressure, sulphuryl fluoride artificially maintained as a liquid until liberated. 85
6. The method of refrigeration which comprises liberating at a relatively low pressure liquid sulphuryl fluoride in the vicinity of a body to be cooled. 90
7. The method of refrigeration, which consists in liquefying gaseous sulphuryl fluoride and thereafter releasing the liquid produced, under appropriate control, to permit its return to the gaseous state with resultant removal of heat from the material to be cooled. 90
8. The reversible process of transferring heat, comprising compressing gaseous sulphuryl fluoride to its liquid state with a resultant evolution of heat, and thereafter permitting the vaporization of said liquid with a resultant absorption of heat. 95
9. The process of refrigeration comprising the evaporation of liquid sulphuryl fluoride in the vicinity of the body to be cooled. 95
